STORAGE TANK

Christian A. Price, Borger, Tex.

Application July 11, 1938, Serial No. 218,707

3 Claims. (Cl. 72—13)

This invention relates to storage tanks for liquids, such as oil, water and the like, and its general object is to provide a tank that combines the use of concrete and wood in its construction, in that it is made up of reinforced slabs or blocks of concrete, with strips of wood between the same, the strips allowing for free expansion and contraction of the concrete slabs, without cracking, damaging or displacement thereof, thus eliminating those disadvantageous features which are inherent in tanks of this character composed entirely of concrete, and my tank has all the advantages of a concrete tank over a metal tank, due to its rust-proof non-corrosive qualities and ability to resist erosion and deteriorating agents.

A further object is to provide a tank that includes separable parts which can be readily assembled to erect a tank of any height, and the wooden strips not only allow for expansion and contraction, but provide a leakproof joint, as will be apparent.

Another object is to provide a tank of the character set forth, that is simple in construction, easy to erect, and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a view of a tank constructed in accordance with the present invention.

Figure 2 is a transverse sectional view taken therethrough.

Figure 3 is a fragmentary vertical sectional view.

Figure 4 is a vertical sectional view taken through a tank, with a concrete top cover supported by uprights.

Referring to the drawing in detail, it will be noted that I have illustrated in Figures 1 to 3, inclusive, a tank which includes superimposed cylindrical wall sections, so that it will be obvious that tanks constructed in accordance with the present invention can be made of any height, and suitably braced as shown, but the important feature, is the fact that the tank is made up of concrete blocks or slabs having wooden joint strips between the same for the purpose as clearly set forth in the objects of the invention.

Regardless of whether or not the tank includes one or more sections, it is provided with a concrete base 1 that is shown as being of circular formation, beveled outwardly from its upper edge, and mounted on the base is a circular bottom wall 5 or floor 2 that is of less diameter than the base.

The bottom wall or floor is made up of blocks 3 of concrete reinforced by any well known means, with strips 4 of wood between the same and an annular rim or band 5 surrounding the 10 blocks and strips and which is composed of arcuate strips 6 of wood arranged in end to end relation. The blocks and strips are disposed in fitting association with each other, and may be secured together by suitable binding material.

The cylindrical wall of the tank or each cylindrical wall section, as the case may be, is made up of elongated arcuate or transversely curved slabs 7 of reinforced concrete, having wooden strips or inserts 8 of cross sectional frusto-conical formation between the same and engaged therewith. Secured to the upper ends of the slabs 7 and strips 8, is a circular dividing member 9 composed of arcuate strips 10 of wood. The wall section is of a diameter to fit about the outer circumference of the band 5, as shown, and a dividing member 9 is provided between each wall section.

Hoops or bands 11 are employed for holding the slabs 7 and strips 8 together in binding engagement, and the holding means as shown are of the rod type having their ends secured together by turn buckles 12.

A roof or top cover 13 may be provided for the tank, and as shown in Figure 1 is of conical formation, but is made from reinforced concrete. Brace rods 14 are also provided when the tank is constructed to a height to require the same, and the brace rods are anchored to the base 1 by U-members 15, while the upper ends thereof extend through the roof 13 and are secured thereto by nuts, in the form as shown in Figure 1.

A flat top cover 16 of reinforced concrete may be provided, as shown in Figure 4 and it may be supported by columns or uprights 17, but 45 in any event it rests upon a wooden dividing member 9.

It will be obvious that any suitable inlet and outlet means having valves or the like of any type may be employed for use with the tank, and a ladder or the like, together with suitable openings in the wall or top cover to allow ingress and egress, may be provided, as will be apparent.

It is thought from the foregoing description

that the advantages and novel features of the invention will be readily apparent.

It is to be understood that changes may be made in the construction and in the combination and arrangement of the several parts, provided that such changes fall within the scope of the appended claims.

What I claim is:

- 10 1. A storage tank comprising a base, a bottom wall seated on said base and including concrete blocks, strips of wood between the blocks, an annular rim surrounding the strips and blocks and composed of arcuate strips of wood arranged in end to end engagement, a cylindrical wall seated upon the base in surrounding engagement with said rim and including arcuate shaped reinforced concrete slabs, cross sectional frusto-conical strips of wood between and engaged with the slabs, and said strips of wood providing expansion and leak proof joints between the blocks and slabs.
- 15 2. A storage tank comprising a concrete base, a bottom wall seated on said base and being of a diameter to be spaced from the outer edges thereof, said bottom wall including blocks of reinforced concrete, strips of wood between the blocks, an annular rim surrounding the blocks and strips and made up of arcuate shaped strips of wood having their ends disposed in engagement with each other, cylindrical wall sections

disposed in superimposed relation with respect to each other, the lowermost wall section being seated on said base in surrounding engagement with said rim each wall section including slabs of reinforced concrete, strips of wood between the slabs, an annular dividing member between the wall sections and composed of arcuate strips of wood, all of said strips of wood providing expansion joints between the blocks and slabs, hoops surrounding the cylindrical wall for holding the slabs and strips thereof in binding engagement with each other, a conical top cover for the tank, and brace rods between the top cover and the base.

10 15 3. A storage tank comprising a base, a cylindrical wall seated upon the base and made up of arcuate shaped reinforced concrete slabs, cross sectional frusto-conical strips of wood between and engageable with the slabs and providing expansion and leak proof joints therefor, a top cover for the cylindrical wall, a dividing member between the upper end of the cylindrical wall and the top cover, a bottom wall seated on the base with the cylindrical wall surrounding the same, said bottom wall including blocks of reinforced concrete, strips of wood between the said blocks and providing expansion joints therefor, and uprights between the bottom wall and the top cover for supporting the latter.
